COVERED ELECTRIC FRYING PAN

John P. Theisen, Jacksonville, Ill., assignor, by mesne assignments, to Knapp-Monarch Company, St. Louis, Mo., a corporation of Delaware

Application September 9, 1954, Serial No. 32,229

Term of patent 14 years

(Cl. D81—10)

Fig. 2.

Fig. 6.

*Fig. 3.**Fig. 5.**Fig. 4.*Figure 1 is a top perspective view of a covered electric frying pan embodying my new design;

Figure 2 is a top plan view thereof;

Figure 3 is a side elevation;

Figure 4 is a front view;

Figure 5 is a rear view; and

Figure 6 is a reduced bottom plan view thereof.

I claim:

The ornamental design for a covered electric frying pan, substantially as shown.
